UNITED STATES PATENT OFFICE:

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO.

MANIFOLDING SALES-BOOK.

1,150,096.

Specification of Letters Patent. Patented Aug. 17, 1915.

Application filed July 17, 1912. Serial No. 709,857.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding sales books, and with regard to certain more specific features thereof, to triplicate books.

One of the objects of the present invention is to provide a simple and practical manifolding sales book which may be more rapidly and efficiently manipulated.

Another object is to provide a triplicate sales book which will be of durable construction and inexpensive to manufacture.

A further object is to provide a triplicate book in which the various sets of leaves may be made ready for use with a minimum amount of manipulation and without handling the carbon.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments of this invention, Figure 1 is a perspective view showing the complete book in operative position; and Fig. 2 is a central transverse section of the book in the position shown in Fig. 1.

Similar reference characters refer to similar parts throughout the different views of the drawing.

Referring now to the drawing in detail, 1 denotes a support or rear cover having a top cover 2 flexibly connected therewith by means of a hinge 3. The support 1 also extends to one side to provide a second protecting cover 4 flexibly connected therewith by means of a hinge 5.

Mounted near one end of the support 1 is a pad comprising a plurality of sets of original and duplicate leaves 6 and 7, respectively. These leaves are connected at

their lower ends, at which point is provided a line of perforations 8 whereby the leaves may be readily separated. The duplicate leaf 7 of each set is slightly longer than the original leaf, thereby to provide a stub portion 9 which is bound with a binding strip 10 by means of staples 11 to form the pad. Each duplicate leaf is provided with a line of perforations 12 near its bound edge whereby it may be conveniently separated from the stub. The original leaf, however, extends slightly beyond this line of perforations so that its free end edge is temporarily secured or retained between the bound stub portions of the duplicate leaves. In this manner the original leaf is held against relative movement and yet it is permitted to be more easily and quickly separated, as when making corrections, as will be more apparent from the description of the operation hereinafter set forth. Bound with these sets of leaves and immediately below the binding strip 10 is a double-faced carbon sheet 13 provided with a thumb-notch 14 whereby the sets of leaves therebeneath may be more easily grasped when manipulating the book to arrange a new set.

Secured to one side of the supporting member 1 by means of staples 15 or the like is a triplicate pad 16 of tissue or parchment leaves. In making the book these leaves are inter-leaved with the sets of original and duplicate leaves. That is, the leaves 17, for example, are positioned above the original leaf of each set of original and duplicate leaves. As shown in the drawing, however, when the book is in operative position, the leaf 18 is interposed between the double-faced carbon 13 and the original leaf 6. It will thus be seen that when a transaction is recorded upon the original leaf 6 it will be duplicated upon the duplicate leaf 7 beneath the carbon sheet and also negatively upon the tissue leaf 18. After recording the transaction the tissue leaves are automatically swung to one side by the manipulation of the book into the position shown by the leaf 19. These leaves are adapted to be retained in the book to form one complete record of all the transactions, while the original and duplicate leaves are disposed of as desired.

A convenient method of operating a book of this character is substantially as follows: Assuming the book to be in the position

- shown in Fig. 1, and held in the left hand of the operator, the transactions are recorded in the usual manner and duplicate and triplicate records obtained as above described.
- 5 After completing the transaction, the upper corner, designated by 20 in Fig. 1, is grasped by the right hand of the operator and pulled upwardly and rearwardly. This movement causes the tissue sheet 18 to swing over to a position above the tissue sheet 19 and also causes the carbon sheet which is bound with the pad of original and duplicate leaves to swing backwardly toward the cover 2. A slight movement to the right will separate 15 the set of original and duplicate leaves along the perforations 12 from the stub. The corner 21 of the next original leaf is then grasped between the thumb and first finger of the right hand through the cut-away portion 14 of the carbon sheet and this leaf drawn downwardly toward the operator. This will move the tissue leaf 17 thereabove upwardly sufficiently to allow it to fall back over the duplicate leaf. The carbon sheet 20 will, by tilting the book, if necessary, swing forwardly over the tissue leaf after which the original leaf is returned to normal position and the book is ready for recording the next transaction.
- 25 30 It is thus seen that this invention provides a simple and practical form of sales book which may be manipulated easily and quickly and is adapted to accomplish, among others, all of the objects and advantages 35 above set forth.
- As many changes could be made in the above construction and many apparently widely different embodiments of this invention could be made without departing from 40 the scope thereof, it is intended that all matter contained in the above description or shown in the accompanying drawing shall be interpreted as illustrative and not in a limiting sense.
- 45 Having described my invention, what I claim as new and desire to secure by Letters Patent is:
1. In a manifolding salesbook, in combination, a plurality of sets of original and 50 duplicate leaves, a separate pad of triplicate leaves inter-leaved with said sets of leaves and a single carbon sheet coacting with the upper leaves to produce triplicate copies.
  2. In a manifolding salesbook, in combination, a plurality of sets of original and 55 duplicate leaves bound in pad form, a pad of triplicate leaves inter-leaved with said sets of leaves, and manifolding means bound with said pad of original and duplicate leaves and lying between the duplicate and triplicate leaves of the top set when in operative position.
  3. In a manifolding salesbook, in combination, a pad comprising a plurality of 60 sets of original and duplicate leaves, a sepa-

rate pad of tissue leaves inter-leaved with said sets of leaves, and a single manifolding sheet connected with said first-mentioned pad.

4. In a manifolding salesbook, in combination, a plurality of sets of original and duplicate leaves bound together at one end, a separate pad having a plurality of tissue leaves interposed between the sets of leaves, and a double-faced carbon sheet bound with 70 75 said sets of leaves.

5. In a manifolding salesbook, in combination, a pad comprising a plurality of sets of original and duplicate leaves bound together at one end, the leaves of each set 80 being connected at their unbound ends, a pad of triplicate leaves inter-leaved with said sets of leaves whereby they assume an operative position between the original and duplicate leaves as the top set of leaves is 85 removed and a double-faced carbon-sheet coacting with the upper leaves of both pads.

6. In a manifolding salesbook, in combination, a pad comprising a plurality of sets of original and duplicate leaves, the duplicate leaves being bound together along one end and connected with the original leaves at their opposite ends, a pad of tissue leaves inter-leaved with said sets of leaves, and a double face carbon sheet bound with the 90 95 leaves of one pad having a normal operative position between the tissue leaf and the duplicate leaf.

7. In a manifolding salesbook, in combination, a pad comprising a plurality of sets 100 of original and duplicate leaves, the duplicate leaves being bound together along one end and connected with the original leaves at their opposite ends, a separate pad of triplicate leaves inter-leaved with said sets 105 of leaves, and a carbon sheet connected with said pad having a normal operative position between the triplicate-leaf and the duplicate leaf, said inter-leaved leaves being so positioned and arranged as to fall into operative 110 position when the top leaf of the next set is detached.

8. In a manifolding salesbook, in combination, a support, two kinds of leaves mounted thereon, one kind being longer than the other and the leaves of said kinds being alternately arranged, means for binding the edges of the longer leaves to said support, the free edges of the shorter leaves adjacent the bound edges of the longer leaves being 115 temporarily secured thereby, a carbon sheet bound with said longer leaves adapted to be interposed successively between each pair of long and short leaves, said carbon sheet having a cut-away portion to permit access to the next original leaf therebeneath, and triplicate leaves inter-leaved with said kinds of leaves.

9. In a manifolding salesbook, in combination, a support, two kinds of leaves mount- 120 125 130

- ed thereon, one kind being longer than the other and the leaves of said kinds being alternately arranged, means for binding the edges of the longer leaves to said support, 5 the free edges of the shorter leaves adjacent the bound edges of the longer leaves being temporarily secured thereby, a carbon sheet bound with said longer leaves adapted to be interposed successively between each pair of long and short leaves, said carbon sheet having a cut-away portion to permit access to the next original leaf therebeneath, and a triplicate leaf positioned above each shorter leaf.
- 10 10. In a manifolding salesbook, in combination, a support, two kinds of leaves mounted thereon, one kind being longer than the other and the leaves of said kinds being alternately arranged, means for binding the edges of the longer leaves to said support, the free edges of the shorter leaves adjacent the bound edges of the longer leaves being temporarily secured thereby, a carbon sheet bound with said longer leaves adapted to be
- interposed successively between each pair of 25 long and short leaves, said carbon sheet having a cut-away portion to permit access to the next original leaf therebeneath, and a pad of tissue leaves connected with said support, the leaves of which are positioned 30 above said shorter leaves.
11. In a manifolding salesbook, in combination, a supporting member having a pad of original and duplicate leaves secured near one end thereof, a second pad of triplicate 35 leaves secured along one side, the leaves of said triplicate pad being inter-leaved with the sets of original and duplicate leaves, a carbon sheet connected with one of said pads having a normal operative position beneath 40 the top inter-leaved duplicate leaf, and a top cover for said pads.

In testimony whereof I affix my signature,
in the presence of two witnesses.

EDWARD KIRBY BOTTLE.
